UNITED STATES PATENT OFFICE

138,517

DESIGN FOR A SANDAL OR SIMILAR ARTICLE

Jack Meltzer, New York, N. Y.

Application June 23, 1944, Serial No. 114,165

Term of patent 14 years

(Cl. D7—5)

To all whom it may concern:

Be it known that I, Jack Meltzer, a citizen of the United States, and a resident of New York city, county of Bronx, and State of New York, have invented a new, original, and ornamental Design for a Sandal or Similar Article, of which the following is a specification, reference being had to the accompanying drawing, forming part thereof.

Figure 3 is an enlarged view of a portion of the design, taken substantially in the region between the two parallel dot-and-dash lines in the right-hand portion of Figure 2.

I claim:

The ornamental design for a sandal or similar article, substantially as shown.

JACK MELTZER.
